UNITED STATES PATENT OFFICE.

ELWOOD S. WHITCOMB, OF MELROSE HIGHLANDS, MASSACHUSETTS.

COMBINED GOLF TEE AND SCORE CARD.

Application filed January 2, 1926. Serial No. 78,790.

The object of this invention is to provide a player, starting his round of golf, with a normal folded score card, but containing tees attached on the inside cover of the same score card. At the completion of each hole, as the player is recording his score as he travels between the previous green and the next tee, the player may easily detach one of the many tees (these being preferably in all eighteen—one for each hole) which he can then quickly assemble, thereby providing himself with a firm, yet very accessible means of teeing his golf ball.

These tees are very inexpensive, being made of paper, and fit snugly inside the score card in two flat semi-circular groups or piles, held to the score card by paper stubs from which they are easily loosened. These tees are simply assembled, having slits at either end which fit together, forming a cone-shaped tee of a convenient height for holding and from which to drive a golf ball.

In the accompanying drawings,

Fig. 1 is a perspective view of the inside of the score card, showing the position of the groups, piles, or set of tees;

Fig. 2 is a full length view of the outside of the score card which, when opened, as here shown, measures six inches in length, or a "stymie" measure.

Fig. 3 is a plan view of a tee before being assembled.

Fig. 4 is a perspective view of the tee assembled and fastened, and

Fig. 5 is a side view of the tee with the ball thereon.

Fig. 6 illustrates a further method of uniting the two ends of the tee to make the same more uniform and to conceal the flaps underneath the side.

In Fig. 1, 10 is the inside half of the score card provided for local rules and other stipulations which the special club may desire to place there. Numeral 11 represents the inside half of the score card where a plurality of tees are placed in two bunches, 12 and 13, attached at stubs 14 and 15, which, in turn, are securely held by any sort of clasps 16 and 17.

Fig. 2 shows the score card itself, the blank or tally 18 being for recording the first nine hole score, and indicates at 19 the second nine hole score. Each separate club

may have different score cards, hence this side of the card may be designed according to the requirements of each club.

In Fig. 3 is shown a tee as it appears in the score card. It is semi-circular in shape with slits 20 and 21 which interlock, and for convenience sake the words over and under have been printed at 22 and 23 to aid in more easily and quickly assembling the tee.

In Fig. 4 a tee is shown in position for a ball to be set thereon. It is conical in form with the extremities joined and held securely by the interlocking of the slits 20 and 21.

In Fig. 5 a golf ball 24 is shown as it would rest on the assembled tee ready for the stroke of the player.

Such a combination score card and tee is very practicable and easily adaptable to the various requirements of each club. The practice at clubs now is that each player is provided with a score card before commencing his round of golf. My invention gives to the player a sufficient supply of tees joined with his score card, in a convenient and practicable combination, and all self contained within the folded leaves of the score card.

A further and very important advantage of my present invention is that the small paper tees are quickly dissolved and disintegrated by the weather and form no objectionable obstruction on the golf greens and tees. Furthermore, my paper tees do not mar, nick, or in any way injure the clubs, whereas metal and wooden tees are objectionable because of offering sufficient resistance to mar and nick the clubs used and also dig up the turf or tee and litter the links while getting into the mowing machines, and are generally objectionable.

I have illustrated in Fig. 6 a neater and, indeed, a preferred method of uniting the opposite flaps or ends 22 and 23 of my improved form of tee whereby the flaps are themselves concealed from view and bent under the side walls of the tee. For this purpose, also, I have lettered the flaps "over" and "under," and Fig. 6 shows graphically how the same may be united to show a smooth and attractive truncated cone on which to rest the golf ball. When the en-

tire set of golf tees are used up or torn out, the score card is suitable for retention as a permanent record and souvenir.

Having thus described my invention, what I claim as new is:

In combination, a folding golf score card constituting a cover, a plurality of complementary flat golf tee blanks each detachably secured within said cover, and wholly con-

cealed and protected thereby, perforated 10 tabs for holding said tee blanks within said score card, whereby the tee blanks are independently detachable while the remaining tee blanks are protected by the score card cover.

In testimony whereof, I have signed my name to this specification.

ELWOOD S. WHITCOMB.
